UNITED STATES PATENT OFFICE.

ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

1,234,069.

Specification of Letters Patent. Patented July 17, 1917.

Application filed October 28, 1915. Serial No. 53,472.

To all whom it may concern:

Be it known that I, ARVID H. NERO, a citizen of the United States of America, and residing at New Britain, in the county of 5 Hartford and State of Connecticut, have invented a certain new and Improved Electric Switch, of which the following is a specification.

My invention relates to electric switches 10 and particularly to a flush switch of the push button type commonly employed to control lighting circuits, and the object of my invention is to provide an improved operating mechanism of simple and efficient 15 construction.

In the accompanying drawing.

Figure 1 is a broken plan view of a switch in which my invention is embodied in one form:

20 Fig. 2 is a vertical section therethrough on the line 2—2, Fig. 1:

Fig. 3 is a detached perspective of the switch mechanism *per se* and:

25 Fig. 4 is a vertical section through the mechanism showing the latter in different position from that shown in Fig. 2.

In the embodiment of my invention here illustrated, the present switch comprises an insulating body 10 of cup-shape the bottom 30 13 of which is pierced to permit the operating buttons 11 and 12 to project therethrough. The carrying yoke 14 has loops 15 through which the push buttons pass and is secured in position by long screws 16

35 which pass upward through the end walls of the body and taking into tapped holes in the yoke, while the heads of the screws overlie the metal closure plate 17 and hold the latter seated against the shoulder 18 in the 40 lower faces of the body walls. The interior of the cup-shaped body thus affords a closed switch chamber 19 into which project the switch terminals 20 and 21, the upper offset ends of which are tapped to receive the securing screws 22 by means of which they are 45 held in position. Binding screws 23 and 24 are carried by the upper ends of the terminal plates and lie in wells 25 and 26 opening to the switch chamber 19, but closed by 50 the upper ends of the terminals so that dust and dirt are completely excluded from the chamber.

The switch frame comprises a pair of uprights 27 and 28 bent at right angles to their

from the margins of the latter are tapped to receive the securing screws 29^a by means of which the frame is rigidly secured to the inner face of the cup button 13. Each upright 27 and 28 is longitudinally slotted at 32 and 33 to receive the margins of the plates 34 and 35 of the push buttons 11 and 12 respectively, in order to insure a rectilinear motion of the buttons in both directions on the actuation of the switch. Bearing lugs 36 are struck outwardly from each of the uprights between the guide slots to form the axis of the oscillating switch lever 37, the legs of which are perforated at 38 to engage the lugs 36. The uprights are 40 also perforated in register at 39 to form 60 bearings for the short studs 40 carried by the legs 41, 42, of the rocker bar 43 which in assembled position lies between the standards 27 and 28 of the switch frame. The 45 switch lever 37 and rocker bar 43 thus form 65 a pair of yokes, the bridge bars of which lie on opposite sides of their respective axes of oscillation. An actuating spring 44 extends between these bridge bars and is secured thereto at its opposite ends by means 70 of the tongues 45 and 46 struck from the respective bridge bars. The switch blade or blades 47 are secured in any suitable manner 75 upon the sides of the switch lever 37. In 80 the present instance the switch is but a single pole device and consequently only a single switch blade 47 is mounted on the 85 switch lever.

In order to actuate the rocker bar 43, the 90 leg 41 thereof which has the form of a web, is slotted on opposite sides of its axis of oscillation at 48 and 49 to receive the extended lugs 50 and 51 of the push button plates 34 and 35. These lugs extend through 95 the slots 48 and 49 and enter the guide slots 32 and 33 in the web 27 of the switch frame. The opposite leg 42 of the rocker bar 43, instead of being slotted, has the upper face 100 of its web shaped to the contour of the slots 48 and 49 of the web 41 and this surface is engaged by the shoulders 54 and 55 on the opposite margins of the push button plates 34, 35. In this way an even pressure is exerted on each side of the rocker bar, while 105 the push buttons are detained in engagement with the rocker, by reason of the entry of the lugs 50 and 51 into the slots 48 and 49 of web 41.

The operation of the switch is readily un-

derstood. Upon the depression of button 11 from the position which it occupies in Fig. 2 to the position shown in Fig. 4, the rocker bar 43 is tilted on its axis. As the bridge bar of the rocker rises during this motion it tensions the spring 44 so that as soon as the upper end of the spring has passed the axis of oscillation 36 of the switch bar 37, it throws the latter from its position of rest 10 against the stop lugs 52 on one side of the frame against the stop lugs 53 on the opposite side of the frame. This results in the shifting of the switch blade 47 from its out of contact position in Fig. 2 to contact position, Fig. 4, in which the blade spans the space between the switch terminals 20 and 21 and thus closes the circuit. The throw of the rocker bar 43 is limited by its impingement against the bridge bar of the 20 switch lever 37 and no other stops are necessary for this purpose.

The construction shown is simple and the metal parts are readily manufactured by stamping from sheet metal, while the shape 25 of the porcelain is simple and requires no intricate die work. Various modifications and details of construction will readily occur to those skilled in the art without departing from what I claim as my invention.

I claim as my invention:—

1. In a push button switch, a switch frame carrying a pair of opposed plates having therein registering pairs of guide 30 slots, a pair of push buttons rectilinearly guided in said slots, a pivoted slotted rocker having a sliding actuating connection through its slots with said buttons, a pivoted switch lever, said rocker bar and switch lever 35 having each a cross arm lying substantially parallel to the axis of oscillation of each of said levers but on opposite sides thereof, in combination with a switch spring extending between said cross arms and serving to 40 actuate the switch lever when the end of the spring secured to the rocker cross arm is moved past the axis of oscillation of the switch lever by the actuation of the push 45 buttons.

2. In a push button switch, a switch frame carrying a pair of opposed plates having therein registering pairs of guide slots, a pair of push buttons rectilinearly guided in said slots, a pivoted slotted rocker 50 yoke having a sliding actuating connection through its slots with said buttons, a pivoted switch lever yoke, said rocker and switch yokes having their bridge pieces lying on opposite sides of the axis of the switch lever, 55 in combination with a switch spring extending between said bridges and serving to actuate the switch lever when the end of

the spring secured to the rocker yoke bridge is moved past the axis of oscillation of the switch lever by the actuation of the push 65 buttons.

3. In a push button switch, a switch frame carrying a pair of opposed plates having therein registering pairs of guide slots, a pair of push buttons rectilinearly guided in 70 said slots, a pivoted slotted rocker yoke having a sliding actuating connection through its slots with said buttons, a pivoted switch lever yoke, said rocker and switch yokes having independent axes of oscillation and their 75 bridge pieces lying on opposite sides respectively of said axes, in combination with a switch spring extending between said bridges and serving to actuate the switch lever when the end of the spring secured to the rocker yoke bridge is moved past the axis of oscillation of the switch lever by the 80 actuation of the push buttons.

4. In a push button switch, a frame having a pair of uprights, a rocker bar yoke, a 85 switch lever yoke, both of said yokes being pivoted on the uprights of said frame, one between said uprights and the other outside said uprights, stops on the uprights limiting the extent of oscillation of one of said 90 yokes, the other yoke having members bearing against the bridge piece of said first yoke in the stop position of the latter.

5. In a push button switch, a frame having a pair of uprights, a rocker bar yoke 95 pivoted on and lying between said uprights, a switch lever yoke pivoted on but outside said uprights, stops on the uprights engaging the bridge of the switch lever yoke to limit the extent of oscillation of said 100 switch lever and means on the rocker bar engaging the bridge of the switch lever in stop position to limit the extent of oscillation of the rocker bar.

6. In a push button switch, a frame having a pair of uprights, a rocker bar yoke pivoted on and lying between said uprights, a switch lever yoke pivoted on but outside said uprights, stops on the uprights 105 engaging the bridge of the switch lever yoke to limit the extent of oscillation of said switch lever and webs on the rocker bar legs adapted to be engaged by the push buttons and extended to engage the bridge of the switch lever in stop position to limit 110 the extent of oscillation of the rocker bar.

In testimony whereof I have signed my name to this specification, in the presence of two subscribing witnesses.
